Primary Examiner — Rashida Johnson(74) *Attorney, Agent, or Firm* — Ostrolenk Faber LLP(57) **CLAIM**

The ornamental design for a shorts, as shown and described.

DESCRIPTION

FIG. 1 is a front elevational view of shorts showing my new design;

FIG. 2 is a rear elevational view thereof;

FIG. 3 is another rear elevational view thereof; the rear flap shown in an opened position;

FIG. 4 is a right side elevational view thereof; the rear flap shown in a closed position; and,

FIG. 5 is a right side elevational view thereof; the rear flap shown in an open position.

Portions of the design shown in broken lines form no part of the claimed design.
